(57) **CLAIM**

The ornamental design for a paper product sheet, as shown and described.

DESCRIPTION

FIG. 1 is a top view of a first embodiment of a paper product sheet in a position of use within a paper roll drawn in broken lines and illustrated in perspective; and, FIG. 2 is a top plan view of a second embodiment of a paper product sheet.

The inner broken line surrounding the paper product sheet depicts the boundary of the claim and forms no part thereof. The broken lines, grayscale features and areas outside of the boundary depict environmental subject matter that forms no part of the claimed design.
